PUSH-OPERATOR SWITCH CONSTRUCTION

Leo L. Verkuil, Norwalk, Conn., assignor to Edwards Company, Inc., Norwalk, Conn., a corporation of New York

Application November 15, 1952, Serial No. 320,717

18 Claims. (Cl. 200—159)

This invention relates to manually operated electric switches, sometimes called "pushes," in which switch actuation is achieved by depressing or pushing a manual operator.

One of the objects of this invention is to provide a compact and dependably acting push switch in which the parts may be individually efficiently manipulated and easily and readily assembled. Another object is to provide a push switch of few parts, held in assembled relation by means that are easily manipulated. Another object is to provide a push switch of the above-mentioned nature in which the several parts, upon assembly, are successively interengaged or interfitted as the sequence of assembly proceeds, thus to avoid use of a succession of separate fastening devices or machine tool operations to complete and hold the parts assembled. Another object is to carry out the last-mentioned object by constructing the several parts so that the manual operations of assembly are simple, easy and foolproof, thus also to avoid risk of breakage or distortion of parts in course of assembly.

Another object is to provide a push switch of the above-mentioned type which in its operation is electrically and mechanically efficient and, more particularly, to provide a push switch in which electrical contact points or areas may be kept clean and effective by dependably achieved rubbing action in response to actuation of the push or operator and in which also long-lasting opposing spring action on the operator may be dependably achieved.

Another object is to provide a push switch of the above-mentioned nature in which parts may be readily formed or constructed individually, as by molding, die-casting, or the like, and in a manner to facilitate assembly and mechanical and electrical coactions. Another object is to provide a push switch in which the push or operator is depressible by a pivoting action and it and its support are constructed for ease of assembly and, when, assembled, to provide a substantial range, within limits, of bodily motion when depressed to insure switch contact actuation.

Another object is to provide a push switch of the above-mentioned nature adapted for simplicity and facility of installation, both mechanically and electrically. Another object is in general to provide improved push switch constructions and installations; other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which several embodiments of the invention are shown by way of illustration and in which similar reference characters refer to similar parts throughout the several views,

Figure 1 is a plan view of a push switch construction adapted for surface mounting, as upon or against a wall surface;

2

Figure 2 is a front elevation, as seen from the bottom of Figure 1;

Figure 3 is a bottom view as seen along the line 3—3 of Figure 2, showing certain of the operating parts;

Figure 4 is a longitudinal central sectional view as seen along the line 4—4 of Figure 1 and of Figure 3;

Figure 5 is a plan view like that of Figure 1 but with the operating parts removed;

Figures 6 and 7 are transverse sectional views taken respectively along the lines 6—6 and 7—7 of Figure 5;

Figure 8 is a longitudinal sectional view as seen along the line 8—8 of Figure 5;

Figures 9 and 10 are respectively a top elevation and a side elevation of the manual operator or "push";

Figure 11 is a transverse sectional view of the manual operator as seen along the line 11—11 of Figures 9 and 10;

Figure 12 is a perspective view of a contact and assembly spring;

Figures 13 and 14 are a plan view and front elevation of a modified form;

Figure 15 is a bottom plan view of the casing of Figures 13 and 14;

Figures 16, 17 and 18 are sectional views along the lines 16—16, 17—17, and 18—18 of Figure 15;

Figure 19 is a top plan view, Figure 20 is a front elevation, Figure 23 is a bottom plan view, and Figures 21 and 22 are respective end elevations, of an insulating bridge plate, and

Figure 24 is a bottom view as seen along the line 24—24 of Figure 14;

Figure 25 is a plan view of a mounting device for securing the modified form of switch construction to a wall surface or the like, and

Figure 26 is a front elevation of a modified form of construction, with certain parts broken away to show, along the line 26—26 of Figure 13, how the structure may be installed on the face of a wall or the like.

Referring first to Figures 1, 2 and 3, I provide a main support generally indicated by the reference character S¹ which, where the switch construction is to be secured against the face of a wall or the like, is preferably constructed in the general form of an elongated housing which can be open on its bottom side, illustratively as by

providing its top face or wall 20 with opposed side walls 21—22 and opposed end walls 23—24, the continuous edges of these walls (see Figure 3) falling in the same plane and being thereby adapted to rest flatwise against a wall surface to which the structure S¹ may be ultimately secured in any suitable manner. Illustratively, at the respective ends of the housing-like support S¹ I may provide countersunk screw holes 25, 26 that extend downwardly (see Figure 4) through tapered internal bosses 27, 28 respectively, the end faces of the latter terminating in the above-mentioned plane of the wall edges; these bosses

are of advantage where the housing is molded out of moldable and curable plastic compounds for the bosses take up compression strains caused by the securing screws and protect the top and side walls of the housing against strain or distortion. The tapered or frusto-conical external shape of the bosses (Figure 8) and preferably also a slight outward canting of the inside faces of the four walls facilitate the molding operation and the withdrawal of the separable mold parts, one of which has a configuration to conform the under side of the parts of the structure S¹ as seen from below in Figure 8 and the other of which is shaped to coact therewith to conform the upper sides thereof as viewed from above in Figure 8.

As is better shown in Figures 1 and 5, the top wall 20 has therein an elongated opening 30 illustratively rectangular in shape, being of a length (see Figures 4 and 8) to fall short at its two ends of the screw-receiving bosses

27, 28, and being of a width (see Figure 5) materially less than the inside spacing between the opposed side walls 21, 22.

It is through the top wall opening 30 that the manual operator 31 projects, the latter being of a width relative to the width of the opening 30 to provide ease of up-and-down motion as viewed in Figures 2 and 4, the operator 31 being substantially of inverted U shape in cross section, as appears better from Figures 9, 10 and 11, having a substantially flat top wall 32 with depending parallel side walls 33, 34, which can coact with the opposed longitudinal edges of the opening 30 (Figures 1 and 6) in guiding the operator 31 in its up-and-down movement relative to the top casing wall 20.

At its right hand end the operator 31 is provided with laterally projecting aligned trunnions or pivot studs 35, 36, preferably integrally formed with and projecting laterally from the depending side walls 33, 34 respectively. These trunnions 35, 36 are provided with half-bearings 37, 38 respectively (Figure 3, 4, 5 and 8) formed in internally thickened portions 21^a, 22^a of the side walls 21, 22, being in the form of a downwardly open slot whose bottom end is arcuate throughout about 180°, preferably of a radius somewhat in excess of the radii of the trunnions or pivot studs 35, 36 themselves, so that the trunnions can be entered into their half-bearings from the open under side of the support structure S¹. The outer sides of these slot-like half-bearings 37, 38 are closed off by the side walls 21, 22 respectively, as is indicated in Figure 5 and as is better shown in Figure 3, the respective outer ends of the trunnions being neatly receivable between the inside faces of these side walls.

With this arrangement of trunnions and half-bearings the operator 31 is assembled to the structure S¹ and entered into the top wall aperture 30 from the open under side of the support structure S¹ and with the trunnions 35, 36 seated in their respective half-bearings 37, 38, the latter limit the extent to which the right-hand end of operator 31 as viewed in Figures 1, 2 and 4 can project into or through the top wall aperture 30, and the parts may illustratively be so proportioned that the right-hand end of the top wall 32 of operator 31 projects only slightly above the housing top wall 20 and it may terminate snugly adjacent the right-hand edge of the aperture as seen in Figures 1 and 4, and if desired, it may be given a suitable degree of curvature (see Figures 4 and 10) so as to more or less merge the operator top wall 32 into the top wall 20 of the housing as the operator 31 partakes of pivoting movement, as is later described, about the axis of the trunnions and half-bearings. At its left-hand end the operator 31 is provided with an end wall 40, which is integral with top wall 32 and with the parallel side walls 33, 34, thus also giving the U-shaped cross section of the operator 31 good strength and rigidity, particularly at the left-hand end which, as will later be seen, is the end that projects upwardly from the housing top wall 20 to a substantial extent so that finger pressure can be readily applied to it to depress it by a counterclockwise pivoting motion viewed in Figure 4; this reinforcing end wall 40 is extended downwardly and toward the left (Figures 4 and 10) to provide a tongue 41 which, with the trunnions at the other end seated in the bearings and thus holding the operator 31 against lengthwise shift, extends underneath the housing top wall 20 just to the right of the screw-receiving boss 27 (see Figure 4) so that it can and does limit the extent to which the left hand of operator 31 projects above the top wall 20, coacting also with the top wall 20 as a stop means to limit upward or clockwise pivoting of operator 31 about the trunnion and bearing axis when urged and biased in clockwise direction by spring means about to be described.

The operator 31 is made of a suitable non-conductive material and is preferably made out of a moldable and curable plastic, being thus unitary or one-piece throughout. Integrally molded with it is a small stud-like pro-

jection 42 (Figures 4, 9, 10 and 11) directed downwardly from the under side of the operator top wall 32 and positioned along the longitudinal center line of the latter and appropriately spaced from the opposite ends of the operator 31. Projection 42 coacts with the top wall 32 and the side walls 33, 34 of the operator to locate and assemble the operator 31 relative to the long arm 43 of a U-shaped spring 44 (see Figure 12 and also Figure 4). Spring 44 is shaped up out of flat stock of good conductivity and good spring action or resiliency, such as Phosphor bronze, and in width its arm 43 is neatly received between the operator side walls 33, 34, projection 42 entering a hole 46 in arm 43 so that the latter or an appropriate portion thereof can rest flatwise against the under face of the operator top wall 32. In Figure 4, the portion of the arm 43 to the right of the projection 42 is neatly nested between the side walls 33, 34 and against the under face of top wall 32, the curvature of which, particularly at its right-hand end as above described, can aid in extending this interfitting or seating to include a portion of the arcuate bend in the spring 44 that joins the long arm 43 to the short arm 45, which is substantially parallel thereto when the parts are assembled (see Figure 4). The hole 46 in long arm 43 is somewhat elongated along the axis of arm 43, permitting slight longitudinal shift of the spring arm 43 relative to the projection 42. The portion 47 of the long spring arm 43 that extends to the left of the projection 42 (Figure 4) is conformed or curved downwardly as viewed in Figures 4 and 12, so that its free end is materially spaced downwardly from the under face of the operator top wall 32.

Provision is made for anchoring the short arm 45 of spring 44 and for making an electrical connection thereto, and also for supporting and positioning a contact and terminal connector with which the resilient or yieldable free end 47 of the long spring arm 43 may coact, and for these purposes I provide a plate-like bridge structure, generally indicated by the reference character 48 which may be integrally formed with the housing or support structure S¹, particularly where the latter is made or molded or cast out of a non-conductive material, such as any suitable moldable and curable plastic compound, and in the form shown in Figures 1-8 this bridge-like structure 48 is molded integrally and extends horizontally between the side walls 21, 22, preferably at the thickened portions 21^a, 22^a thereof, as is better indicated in Figures 3 and 5. In general cross-sectional conformation, as along the lines 6-6 and 7-7 of Figure 5, the structure S¹ is somewhat H-shaped throughout the longitudinal extent of the bridge structure 48, as better appears from the sectional views in Figures 6 and 7, thus providing a conformation that facilitates molding by separable mold parts operable from both above and below as viewed in Figures 6 and 7 and also Figure 8.

The under face of the cross bridge 48, as better appears in Figure 8, is substantially flat except for a downwardly projecting cross rib 50 (Figures 3, 4, 6 and 8) and except for a parallel cross part 51 later described. Cross rib 50, which also coacts with the short spring arm 45 as is later described, serves as a physical and insulating barrier or separator in that the cross bridge 48, to the left of the rib 50, is provided with a centrally positioned hole 52 which is threaded to receive a screw 53, under the head of which an electrical conductor may be clamped and the inner free end of which projects upwardly through the bridge 48 and underlies the springy free end 47 of the spring 44 for coaction therewith in making and breaking a circuit as the operator 31 is manually depressed and released.

The cross part 51 may be said to be of inverted U shape, as is better shown in Figure 5, in that its upper face or edge is spaced downwardly from the plane of the under face of the bridge part 48 (Figures 7 and 8) so that it coacts with the under face of the bridge part 48 to form a slot 54 of a width (Figures 7 and 3) and of a vertical

dimension (Figures 4 and 7) substantially matching the width and thickness of the short springy arm 45 so that the free end of the latter may be slid toward the left (in Figures 5 and 8) along the under face of the bridge part 48 to enter it into and pass it through this slot 54 (Figure 7) until it abuts against the right-hand side of the barrier rib 50; when so halted by the barrier rib 50 a hole 55 (Figure 12) in the short spring arm 45 is brought into registry with a threaded hole 56 in the bridge part 48, whereupon a screw 57 is threaded into the threaded hole to hold the spring 44 against retrograde or disassembling movement toward the right; under the head of screw 57 an electrical conductor is clamped, thus also clamping the spring arm 45 against the under face of the bridge part 48 and dependably holding the short spring arm 45 for good coaction of the long spring arm 43 with the manual operator 31 which the U-shaped spring 44 normally biases and holds in assembled relation in that the right end of operator 31, whether it does or does not project beyond the top wall 20 of the housing, is biased upwardly, as viewed in Figure 4, to hold the trunnions 35, 36 seated in their respective half-bearings 37, 38 as above described, and in that the left-hand end of the operator 31 is biased and projected upwardly beyond the housing top wall 20 to the extent permitted by the engagement of the tongue 41 (Figure 4) with the stop ledge formed by the top wall 20, as earlier above described.

The depressible left end portion of operator 31 is thus maintained in external prominence, and it is to that portion that any person desiring to actuate the switch would direct a finger of the hand for depressing the operator. When the latter is depressed the springy free end 47 of the long spring arm 43 is brought into rubbing coaction with the inner contact end of binding screw 53 (see Figure 4), thus ease of actuation and increased rubbing action are facilitated by the longitudinal movement of spring arm 43 relative to the operator 31 permitted by the elongated hole 46 in the spring to maintain clean and bright the respective engageable contact surfaces or points. These rubbing actions take place in reverse direction upon release of the operator. Projecting springy contact part 47 is protected against being over-stressed toward the top wall 32 of operator 31 in that its yieldability under contact pressure is limited by the limited downward movement of operator 31 whose side walls 33, 34 contact the bridge part 48 as is later described, preventing spring part 47 from being jammed against top wall 32.

The straight-line distance between the right end of the bridge part 48 and the right end edge of top wall aperture 30 (see Figure 4, and particularly Figure 8) is substantial in relation to the vertical dimensions of the operator 31 as the latter is viewed in Figures 10 and 11, and is sufficient, for purposes of assembly of the parts, to permit the free passage upwardly therethrough of the left-hand end of the operator 31, with the tongue 41 being the leading edge as this movement of assembly is proceeded with. Preferably, before starting this movement of assembly, the long arm 43 of spring 44 is laid in position against the under side of operator 31 as above described, with the projection 42 of the operator and the hole 46 of the long spring arm 43 interengaged so that the long arm 43 accompanies the operator 31 as the latter is manually guided upwardly and toward the left in Figure 8 through the just mentioned spacing or opening until the trunnions 35, 36 reach the opposed ledges 21^a, 22^b (Figure 5) of the thickened side walls 21^a, 22^b just to the right of the half-bearings 37, 38 respectively (Figures 5 and 8), and with the trunnions just about engaging the just mentioned ledges the short spring arm 45 is pressed against the flat under face of the bridge part 48 just to the right of the inverted U-shaped cross piece 51 and the left end of the operator 31 is depressed to enter the tongue 41 past the left-hand edge of the top wall aperture 30, whereupon the sub-assembly of operator 31 and spring 44 is slid to the left to enter the short

5 spring arm 45 into the slot 54 and into abutting relation to the barrier cross rib 50, that movement bringing the tongue 41 underneath the stop ledge formed by the top wall 20 just to the right of the screw-receiving boss 27 (Figure 4). The screw 57 is passed through the spring hole 55 and threaded into the cross bridge hole 56 and the assembly is complete.

6 In order to facilitate the molding of the U-shaped cross part 51 and the formation of the above described spring-receiving slot 54, in the same molding operation in which the housing structure S¹ is formed, the upper side of the cross part 51 is juxtaposed to a transverse slot 58 (Figures 7 and 8) in the cross bridge part 48; the slot 58 is formed by that downwardly projecting portion of the upper mold part which conforms the upper face or faces of the inverted U-shaped cross piece 51, the upper cross face of the latter being spaced downwardly (see Figure 7) from the under face of the bridge part 48 by an amount equal to the thickness of the spring 44, and in that manner an under half-seat for the short spring arm 45 is formed by the upper mold part against which the under side of the short spring arm 45 may rest, while companion half-seats, such as the several portions of the under face of the bridge part to the right and to the left of the cross part 51, are formed by the lower mold part against which the upper side of the short spring arm 45 may rest, these several half-seats, together with the side parts of the inverted U-shaped cross piece 51 forming the bearing slot into which the short spring arm 45 is entered is above described. To the right of the barrier cross rib 50 (see Figure 8) the half-seat formed by the under face of the bridge part 48 is curved or beveled off, as is better indicated in Figure 8, so as to guide the free end of the short spring arm 45 onto the under face of the bridge part 48 as it emerges to the left of the cross part 51.

The construction can be embodied in compact and relatively diminutive form and several other features may be provided to coact toward achieving improved compactness; for example, the shell or housing structure S¹ may be made of lesser vertical height at its left-hand end, as is better shown in Figures 2, 4 and 8, by tapering the side walls 21, 22 as shown in Figure 2, and by slanting the top wall 20 downwardly to the left (Figures 2, 4 and 8), thus lowering the stop ledge at the left end of the top wall aperture 30 (Figure 4) so that the tongue 41 on the pivoted operator 31, when in engagement with the stop ledge, holds the top face of the operator 31 substantially horizontal, giving the effect (see Figure 2) of tapered-off side walls 33, 34 of the operator 31 as the latter merges and disappears into the top wall opening 30, at which its right end is of greater height than at its left end. These relationships of the parts bring the left end of operator 31, being the end remote from the pivoting trunnions 35, 36, normally (see Figures 2 and 4) into major prominence as it projects upwardly from the downwardly inclined top face 20, for application thereto of finger pressure rather than at the right-hand end, where the operator virtually merges into the slanting top face and does not project so much. As is better shown in Figures 5 and 6, the plate-like bridge part 48 is provided with spaced parallel grooves 61, 62 which are of progressively greater depth in a direction from the right to the left in Figure 5, and they are positioned to underlie the side walls 33, 34 respectively of the operator 31; accordingly, when the operator 31 is pivoted counter-clockwise in Figures 2 and 4 in response to manual depression, the operator side walls 33, 34 can enter these grooves 61, 62 respectively, thus providing a greater length of actuating movement of the operator without having to increase over-all height of the structure.

In Figures 13-24 I have illustratively shown a modified embodiment of certain features of my invention adapted to carry out the latter, where the casing structure such as the structure S¹ above described is made of metal, as 75 by die-casting, or as by forging out of brass, or the like.

In Figures 13-17 a housing or casing structure that may be so constructed is generally indicated by a reference character S^2 , and as in the form above described it has a top wall 20 with opposed side walls 21, 22, and opposed end walls 23, 24, being also generally elongated in shape and having a central substantially rectangular aperture 30 in its top wall 20 for receiving therein and for coaction with the top wall 20 of the manual operator 31 above described. It has internally thickened portions 21^a, 22^a for its respective side walls 21, 22, conformed adjacent their right-hand ends (Figures 15, 16) to provide open half-bearings 37, 38 respectively for receiving the trunnions 35, 36 of the manual operator 31. To the right of the downwardly open half-bearings 37, 38 these thickened wall portions 21^a, 22^a have ledges 21^b, 22^b respectively, substantially like those above described in connection with Figures 5 and 8, and to the left of these half-bearings these thickened side wall portions 21^a, 22^a are conformed to provide downwardly facing opposed and parallel flat ledges 21^c, 22^c respectively (see Figures 15, 17), and in the form disclosed the faces of these ledges fall in the same plane, a plane that is parallel to but spaced upwardly from (Figures 16, 17) the plane of the edges of the opposed side and end walls of the opposed side and end walls of the casing structure S^2 .

These parallel spaced ledges 21^c, 22^c form opposed seats for a non-conductive plate-like bridging part shown in Figures 19-23 and generally indicated by the reference character 48^a inasmuch as it is, in configuration and interrelationship of its several parts, the same as the bridging part 48 above described in connection with Figures 1-12, excepting that it is separately molded out of any suitable non-conductive plastic composition and excepting that it is provided with opposite and parallel side edges 63, 64, which are spaced and dimensioned to be just snugly received between the vertical internal side walls 21^c, 22^c (Figures 15 and 17) which form the outer or lateral boundaries for the ledges 21^c, 22^c respectively against which the plate-like bridge 48^a rests, with its parallel grooves 61, 62, of increasing depth toward the left in Figures 20, 24, facing upwardly, and with the transverse barrier rib 50 and the transverse part 51 which coacts in forming the slot 54 facing downwardly.

The bridging plate 48^a may be secured in position in any suitable manner. For example and as shown in Figures 15-17, the opposed bridge-supporting ledges 21^c, 22^c may be provided with holes 65, and the opposed longitudinal side portions of the bridging member 48 may be provided with slots 66 (Figures 19, 23) which open into the longitudinal side edges and which are dimensionally located so that they can respectively register with the holes 65 (Figure 15) in the supporting ledges. Upon being brought into such registry the bridging member 48^a may be secured in position as by headed pins that pass through the slots 66 and are press-fitted into the holes 65, or as by screws, which may be of the type that have a large pitch and are constructed to cut their own threads in the walls of the holes 65, such securing means being indicated in Figure 24 by the reference character 67. Desirably, to locate bridge member 48^a appropriately with respect to the trunnion-receiving half-bearings 37, 38 and with respect to the opening 30 in the top wall 20, the vertical faces 21^c, 22^c (Figures 15, 17 and 24) between which the opposed longitudinal side edges of the bridge plate 48^a are received, are provided with vertical shoulders 21^f, 22^f respectively, the faces of which are at right angles to the side faces 21^c, 22^c. There are thus formed two opposed right angle corners, into which two corners of the insulating bridge plate 48^a are respectively receivable, and preferably the relationships of other parts are such that the bridging part 48^a can be seated against the ledges 21^c, 22^c and secured in place in only one position relation relative to the casing structure S^2 and its various parts.

Thus, referring to Figures 19 and 23, the four corners

of the bridging member 48 are indicated by the reference characters *a*, *b*, *c*, *d*; the longitudinal spacing from the edge *a*-*b* of the transverse center line of the slots 66-66 adjacent thereto is the same as the longitudinal spacing of the aligned vertical shoulders 21^f, 22^f (Figure 15) from their respectively adjacent holes 65 in the two ledges, whereas the spacing from the edge *d*-*c* (Figures 19, 23) of the transverse center line of the respectively adjacent slots 66-66 is greater than these just described spacings. Accordingly, were the bridging plate 48^a to be rested against the ledges 21^c, 22^c with the corners *c*-*d* at the shoulders 21^f, 22^f respectively, the slots 66 would be completely out of registry with the holes 65 in the ledges, and the securing devices could not be inserted; the bridging plate 48^a must, therefore, be turned end for end. Moreover, and as is better shown in Figures 20-23, the parallel cross rib parts 50, 51 which project from the under face of the bridge plate extend completely across and from edge to edge, and therefore they preclude flatwise seating of the bridge member 48^a against the ledges 21^c, 22^c so that the bridging part cannot be assembled to the ledges in upside-down relation and can be seated thereagainst only with the cross rib parts 50, 51 facing toward the open bottom end of the casing structure S^2 . Accordingly, seating and securing cannot be effected unless corner *a* is at the shoulder 21^f and corner *b* is at the shoulder 22^f. These coactions to facilitate proper orientation of the plate-like bridge member 48^a in course of assembly may be aided by making the longitudinal side portions of the plate member 48^a of lesser thickness where they overlie the ledges 21^c, 22^c, as is better shown in Figures 21, 22, where these side portions are indicated at 68 and 69; it is in these thinner side parts 68, 69 that the slots 66 are provided, leaving a thicker or upwardly projecting central portion 70 whose parallel vertical sides are just snugly receivable within and between the parallel vertical faces of the longitudinal sides of the aperture 30 in the top wall of the casing S^2 .

With the plate-like member 48^a of insulating material located and secured in position relative to the trunnion half-bearings 37, 38 and relative to the casing and opening 30, assembly of the operator 31 and contact spring 44 and conductor screws can proceed in the manner above described in connection with Figures 1-12; again, the opening or spacing through the resultant sub-assembly of casing S^2 and bridge plate 48^a is greater at the right-hand end as viewed in Figure 24 than it is at the left-hand end of the bridge 48^a and, accordingly, the tongued end of the operator 31, with the long spring arm 43 set into the under side of the operator, is entered into and through this larger passageway and is guided toward the left-hand end of the top wall opening 30 and, with the trunnions 35, 36 resting upon the ledges 21^b, 22^b respectively, the tongued end is depressed downwardly into the left end of the aperture 30 and operator and spring are then shifted to the left to enter the short spring arm 45 through the slot 54 at the under side of the plate bridge 48^a and to enter the trunnions 35, 36 into their respective half-bearings 37, 38, all as above described, whereupon the screws 53, 57 (Figure 24) are threaded into their respective threaded holes 52, 56 in the bridge 48^a, both screws serving to bind or clamp the two circuit conductors, with screw 53 serving as the fixed contact for coaction with the movable contact spring part 47 and with screw 57 serving to hold the short spring arm 45 against downward displacement as viewed in Figure 4.

With assembly completed the device may now be secured to any suitable support, usually against the surface of a wall or door frame or the like, preferably by means of a mounting member, generally indicated by the reference character 71 and better shown in Figures 25 and 26, the member 71 being constructed for coaction with certain features embodied in the housing or casing S^2 . As appears better from Figures 15-18, the ledges 21^b, 22^b, formed by thickening the side walls 21, 22 respectively

are extended toward the right, in Figures 15 and 16, toward the casing end wall 24, being made to terminate, by thickened side wall portions 21^g, 22^g, shaped as is better shown in Figure 16, in transversely aligned sockets 73, 74, the thickened side wall portions 21^g, 22^g, presenting edge faces 21^h, 22^h, which are parallel and are inclined upwardly and toward the end wall 24 (see Figure 16), forming equal acute angles with the horizontal ledges 21^b, 22^b. These two acute angles form the above-mentioned sockets 73, 74, and as is better shown in Figure 24, these sockets are spaced a substantial distance from the pivoted end of the manual operator 31 and hence are well spaced away from the U-bend in the spring 44.

The mounting member 71 (Figures 25 and 26) can be in the form of a simple sheet metal stamping of a width to be neatly receivable between the longitudinal side walls 21, 22 of the casing S², and at its opposite ends it is bent upwardly as at 75, 76, and adjacent the bent ends 75, 76 the member 71 is provided with holes 77, 78 by which, as shown in Figure 26, the member 71 may be secured to a wall by the use of screws 79; intermediate of holes 77, 78 the flat central base portion of the member 71 is provided with an aperture 80, through which the insulated circuit conductors (not shown) may be brought, from a hole in the wall, to the front (upper, in Figure 26) side of the mounting member 71, and connected to the binding screws 53, 57 which, as better appears in Figure 24, are exposed at the under side of the bridging plate 43^a of the assembled switch structure.

The latter is then positioned over the mounting member 71, which is snugly received between the opposed side walls 21, 22, with one of the bent-up end parts, such as part 75, Figure 26, entered into the opposed aligned sockets 73, 74, thus bringing the other end part 76 adjacent and juxtaposed to the end wall 23.

The end parts 75, 76 are bent up at the same angle, an angle which, in relation to the inclination of the edge faces 21^h, 22^h of the sockets 73, 74, gives the outer faces of the bent parts 75, 76 a smaller acute angle with the horizontal as seen in Figure 26 than the acute angle formed with the horizontal by these inclined edge faces. As a result the bent part that enters the sockets 73, 74 can coact with these inclined edge faces 21^h, 22^h with a camming action, and the other part that is juxtaposed to the end wall 23 makes an appropriate acute angle with the latter so that it can coact, by a camming action, with the inner end of a screw 81 (Figure 26) carried in a threaded hole 82 in the end wall 23.

With the mounting member 71 secured to the face of a wall, threading the screw 81 inwardly (Figure 26) and against the bent part 76 locks the casing S² with its switching parts to the member 71, and at the right-hand end a component of the force exerted by the screw 81 against the inclined face of part 76 draws the right-hand end of casing S² tightly against the wall surface, while at the other bent end part 75 the clamping force of the screw 81 is resolved into components by the camming action between the inclined edge faces 21^h, 22^h, and one of these components acts to draw the left-hand end of casing S² tightly against the wall surface.

The cutout or opening 80 in the member 71 (Figures 25 and 26) is of a width and length materially greater than the rectangular area (see Figure 24) within which fall the heads of the binding screws 53, 57, thus precluding contact or engagement of the screws and the bared conductor ends which they secure, with the mounting member 71, and also providing ample clearance space underneath the conductive parts of the switch structure and thus coacting to permit making the housing or casing S² of lesser height. Moreover, the mounting member 71 is preferably symmetrically constructed about its longitudinal and transverse axes as seen in Figure 25, thus facilitating its installation and assembly thereto of the switch structure.

The coaction and functioning in use of the various switching parts of the structure of Figures 13-24 will

now be clear in view of the description thereof in connection with the construction of Figures 1-8. In both forms very few parts comprise the completed switch structure and in each form assembly is speedy, simple and foolproof. Moreover, electrical safety and insulation is dependably achieved. In the illustrative embodiment of Figures 1-8 the casing or housing and manual operator, when made of non-conductive material as by molding out of a suitable plastic, coact in use to dependably maintain the live conductive parts against possible contact by the finger of a person operating the push switch; the side walls 33, 34 of the operator 31 maintain closure of the aperture 30 at its sides during actuation of the operator 31, and particularly also when it is in its normal upwardly projected position. Dependable protection is also achieved in the illustrative form of Figures 13-24, where the construction makes it possible to achieve the advantages of using metal in making the casing structure S², for in this form the insulating bridge 48^a in coaction with the conformation of the operator 31 also dependably maintain the live conductive parts against possible engagement or contact with the metal casing S². In both forms the cross parts 50, 51 at the under side of the bridging part, while coacting in achieving ease and dependability of mounting and support for the contact spring 44, also serve as insulating barriers or separators between the conductor-connector screws 53, 57. While features of advantage may be achieved by slanting the top wall of the casing as in the casing S¹ of Figures 1 and 2, many advantages of my invention may be achieved or retained where the top wall 20 is substantially parallel to the plane of the rear or bottom edges of the side and end walls of the casing as in the form shown in Figures 14 and 16.

It will thus be seen that there has been provided in this invention push switches in which the several objects above noted, together with many thoroughly practical advantages, are successfully achieved.

As many possible embodiments may be made of the above invention and as many changes might be made in the embodiments above set forth, it is to be understood that all matter hereinabove set forth or shown in the accompanying drawings is to be interpreted as illustrative and not in a limiting sense.

I claim:

1. A push switch construction comprising a housing having a top wall provided with an elongated opening and having spaced side walls with a plate-like bridge part of insulating material extending between said side walls and below said opening, means providing aligned spaced half-bearings interiorly of the housing and adjacent one end of said top wall opening, said half-bearings being open toward the bottom of said housing and said bridge part having two threaded holes substantially underneath said opening and aligned lengthwise of the latter with binding screws threaded into said holes from the under side of said bridge part, a U-shaped flat spring, one arm of which is adapted to rest against the under side of said bridge part and has a hole therein through which one of said binding screws passes and the other arm of which is adapted to extend along said elongated top wall opening and substantially overlie the top side of said bridge part for coaction with the other of said binding screws, with the U-shaped bend that joins said spring arms extending into the space adjacent to and between said downwardly open half-bearing and with its axis of bend parallel to the axis of said half-bearings and located in the general region of the axis of said half-bearings, and an elongated manual push operator of insulating material received in said opening and overlying said bridge part, said operator having two laterally spaced depending side walls between which extends said overlying arm of said U-shaped spring, the under side of said operator, between said depending walls thereof, being engaged by said overlying arm of said U-shaped spring whereby said spring arm biases said operator upwardly

and outwardly of said top wall opening, said operator having at that end thereof adjacent said U-shaped bend laterally projecting and coaxially aligned trunnions which are seated in said downwardly open half-bearings and held therein by the upward bias of said U-shaped bend and of said overlying spring arm whereby said operator is pivotally compressible about the axis of said half-bearings and concurrently bends said U-shaped bend about said parallel axis to bring said spring arm into engagement with said other binding screw, said bridge part having laterally spaced grooves in its top side and respectively underlying said spaced depending side walls of the operator for entry of the latter side walls into said spaced grooves upon depression of the operator and said operator having means coacting to limit its upward swing about said axis of said half-bearings under the bias of said spring.

2. A push switch construction comprising a housing having a top wall provided with an elongated opening and having spaced side walls with a plate-like bridge part of insulating material extending between said side walls and below said opening, means providing aligned spaced half-bearings interiorly of the housing and adjacent one end of said top wall opening, said half-bearings being open toward the bottom of said housing, and said bridge part having two threaded holes substantially underneath said opening and aligned lengthwise of the latter with binding screws threaded into said holes from the under side of said bridge part, a U-shaped flat spring, one arm of which is adapted to rest against the under side of said bridge part and has a hole therein through which one of said binding screws passes and the other arm of which is adapted to extend along said elongated top wall opening and substantially overlie the top side of said bridge part for coaction with the other of said binding screws, with the U-shaped bend that joins said spring arms extending into the space adjacent to and between said downwardly open half-bearings and with its axis bend parallel to the axis of said half-bearings and located in the general region of the axis of said half-bearings, and an elongated manual push operator of insulating material received in said opening and overlying said bridge part with its under side engaged by said overlying arm of said U-shaped spring where said spring arm biases said operator upwardly and outwardly of said top wall opening, said operator having at that end thereof adjacent said U-shaped bend laterally projecting and coaxially aligned trunnions which are seated in said downwardly open half-bearings and held therein by the upward bias of said U-shaped bend and of said overlying spring arm whereby said operator is pivotally compressible about the axis of said half-bearings and concurrently bends said U-shaped bend about said parallel axis to bring said spring arm into engagement with said other binding screw, said operator having means coacting to limit its upward swing about said axis of said half-bearings under the bias of said spring, there being a spacing between the end of the bridge part and the end of said top wall opening adjacent to which are said downwardly open half-bearings to provide a passageway that has a cross-section that is bounded, at its sides, by said spaced side walls and, at top and bottom, substantially by the plane of said top wall and by said bridge part, said elongated push operator having a cross-section, transversely of its length, that falls within the boundaries of the aforesaid cross-section of said passageway and, upon endwise longitudinal movement, said elongated push operator is entered through said passage, from the under side of said housing and with the trunnioned end thereof trailing, into said top wall opening and into overlying relation to said bridge part for entry of the trunnions into said half-bearings.

3. A push switch construction as claimed in claim 2 in which the under side of said push operator is conformed to provide an elongated seat for receiving said overlying spring arm thereagainst with said U-shaped

bend adjacent said trunnions whereby said operator may be entered through said passage and into said top wall opening conjointly with said overlying spring arm and with said trunnions and said U-shaped bend trailing and thereby bring the other spring arm into position against against the under side of said bridge part for the passage therethrough and into the threaded hole of the bridge part of the binding screw.

4. A push switch construction as claimed in claim 3 in which the spring arm seat at the under side of said operator is provided by an under face of said operator and two laterally spaced downwardly extending side walls of the operator between which said overlying spring arm is received and longitudinally aligned for conjoint entry as aforesaid.

5. A push switch construction as claimed in claim 4 in which said bridge part has laterally spaced grooves in its top side and respectively underlying said spaced depending side walls of the operator.

6. A push switch construction comprising a housing having a top wall provided with an elongated opening and having spaced side walls with a plate-like bridge part of insulating material extending between said side walls and below said opening, means providing aligned spaced half-bearings interiorly of the housing and adjacent one end of said top wall opening, said half-bearings being open toward the bottom of said housing, and said bridge part having two threaded holes substantially underneath said opening and aligned lengthwise of the latter with binding screws threaded into said holes from the under side of said bridge part, a U-shaped flat spring, one arm of which is adapted to rest against the under side of said bridge part and has a hole therein through which one of said binding screws passes and the other arm of which is adapted to extend along said elongated top wall opening and substantially overlie the top side of said bridge part for coaction with the other of said binding screws, with the U-shaped bend that joins said spring arms extending into the space adjacent to and between said downwardly open half-bearings and with its axis bend parallel to the axis of said half-bearings and located in the general region of the axis of said half-bearings, and an elongated manual push operator of insulating material received in said opening and overlying said bridge part with its under side engaged by said overlying arm of said U-shaped spring where said spring arm biases said operator upwardly and outwardly of said top wall opening, said operator having at that end thereof adjacent said U-shaped bend laterally projecting and coaxially aligned trunnions which are seated in said downwardly open half-bearings and held therein by the upward bias of said U-shaped bend and of said overlying spring arm whereby said operator is pivotally compressible about the axis of said half-bearings and concurrently bends said U-shaped bend about said parallel axis to bring said spring arm into engagement with said other binding screw, said operator having means coacting to limit its upward swing about said axis of said half-bearings under the bias of said spring, said bridge part being provided, at its under side,

with two spaced insulating barrier ribs extending transversely between said two binding screws, the barrier rib that is adjacent the binding screw that passes through the one arm of said spring having a slot-like recess underneath it for receiving therethrough the free end of that spring arm that rests against the under side of said bridge part, the barrier rib that is adjacent the other of said binding screws serving as a stop for said free end of said spring arm.

7. A push switch construction comprising a housing having a top wall provided with an elongated opening and having spaced side walls with a plate-like bridge part of insulating material extending between said side walls and below said opening, means providing aligned spaced half-bearings interiorly of the housing and adjacent one end of said top wall opening, said half-bearings being open

toward the bottom of said housing, and said bridge part having two threaded holes substantially underneath said opening and aligned lengthwise of the latter with binding screws threaded into said holes from the under side of said bridge part, a U-shaped flat spring, one arm of which is adapted to rest against the under side of said bridge part and has a hole therein through which one of said binding screws passes and the other arm of which is adapted to extend along said elongated top wall opening and substantially overlie the top side of said bridge part for coaction with the other of said binding screws, with the U-shaped bend that joins said spring arms extending into the space adjacent to and between said downwardly open half-bearings and with its axis bend parallel to the axis of said half-bearings and located in the general region of the axis of said half-bearings, and an elongated manual push operator of insulating material received in said opening and overlying said bridge part with its under side engaged by said overlying arm of said U-shaped spring where said spring arm biases said operator upwardly and outwardly of said top wall opening, said operator having at that end thereof adjacent said U-shaped bend laterally projecting and coaxially aligned trunnions which are seated in said downwardly open half-bearings and held therein by the upward bias of said U-shaped bend and of said overlying spring arm whereby said operator is pivotally compressible about the axis of said half-bearings and concurrently bends said U-shaped bend about said parallel axis to bring said spring arm into engagement with said other binding screw, said operator having means coacting to limit its upward swing about said axis of said half-bearings under the bias of said spring, in which said housing and said bridge part and the means providing said downwardly open half-bearings being integral and molded in one piece out of moldable and curable non-conductive plastic material.

8. A push switch construction comprising a housing having a top wall provided with an elongated opening and having spaced side walls with a plate-like bridge part of insulating material extending between said side walls and below said opening, means providing aligned spaced half-bearings interiorly of the housing and adjacent one end of said top wall opening, said half-bearings being open toward the bottom of said housing, and said bridge part having two threaded holes substantially underneath said opening and aligned lengthwise of the latter with binding screws threaded into said holes from the under side of said bridge part, a U-shaped flat spring, one arm of which is adapted to rest against the under side of said bridge part and has a hole therein through which one of said binding screws passes and the other arm of which is adapted to extend along said elongated top wall opening and substantially overlie the top side of said bridge part for coaction with the other of said binding screws, with the U-shaped bend that joins said spring arms extending into the space adjacent to and between said downwardly open half-bearings and with its axis bend parallel to the axis of said half-bearings and located in the general region of the axis of said half-bearings, and an elongated manual push operator of insulating material received in said opening and overlying said bridge part with its under side engaged by said overlying arm of said U-shaped spring where said spring arm biases said operator upwardly and outwardly of said top wall opening, said operator having at that end thereof adjacent said U-shaped bend laterally projecting and coaxially aligned trunnions which are seated in said downwardly open half-bearings and held therein by the upward bias of said U-shaped bend and of said overlying spring arm whereby said operator is pivotally compressible about the axis of said half-bearings and concurrently bends said U-shaped bend about said parallel axis to bring said spring arm into engagement with said other binding screw, said operator having means coacting to limit its upward swing about said axis of said half-bearings under the bias of said

spring, said housing is interiorly provided with means forming a seat for said insulating bridge part for positioning it in bridging relation to the housing and said walls, with means securing said bridge part in position, 5 said means forming the seat for said insulating bridge part comprising juxtaposed downwardly facing ledges integrally formed interiorly of the side walls of the housing, the means forming said half-bearings comprising endwise extensions of said ledges with downwardly open arcuate recesses therein to provide said half-bearings, said spring arm seat means of said bridge part comprising a transversely extending projecting barrier of greater length than the spacing between said side walls whereby to prevent assembly of said bridge part to said ledges in up-side-down relation.

9. A push switch construction comprising a top wall having an opening therein for accommodating at least part of a manual push operator and having spaced side walls with a plate-like bridge part extending between 10 the side walls and substantially below said opening, said bridge part being spaced downwardly at one end thereof from the top wall adjacent the opening to provide a substantial passageway therebetween, said passageway at said one end of said bridge part having a cross-section bounded, 15 at its sides, by said spaced side walls and, at top and bottom, substantially by the plane of said top wall and by said downwardly spaced bridge part, said bridge part having a conductor-connector-contact means with the contact part thereof exposed at the top side of the bridge 20 part, a U-shaped flat spring one arm of which is adapted to rest against the under side of said bridge part and the other arm of which extends through said passageway into overlying relation to the top side of said bridge part for coaction with said contact part, an elongated manual 25 push operator having a portion adapted to project upwardly through said opening and transversely projecting means adapted to underlie the top wall adjacent said opening, said elongated push operator being enterable by endwise movement through said passageway in that it 30 has a cross-section, transversely of its length, that falls within the boundaries of the aforesaid cross-section of said passageway and, upon such endwise movement, brought into position over said bridge part and over said second-mentioned spring arm which biases said push 35 operator in a direction outwardly of said opening to an extent limited by engagement of its transversely projecting means with the under side of said top wall, and means for securing said first-mentioned spring arm to said bridge part and for making electrical connection thereto.

10. A push switch construction as claimed in claim 9 in which said push operator and said second-mentioned 40 spring arm are provided with means for holding them together with said spring arm against the under side of said push operator whereby said operator and said spring arm are together entered, through said passageway, into position overlying said bridge part and thereby bring said first-mentioned spring arm into position against the under side of said bridge part.

11. A push switch construction as claimed in claim 10 45 in which said holding means comprises a downward projecting part at the under side of said push operator and a hole in the second-mentioned spring arm for receiving said downward projecting part.

12. A push switch construction as claimed in claim 10 50 in which said bridge part is provided, at the under side thereof, with recess means that is open in a direction generally toward said passageway for receiving and seating therein the end of said first-mentioned spring arm in response to movement thereof resulting from conjoint movement of said push operator and said other spring arm into said passageway.

13. A push switch construction as claimed in claim 9 55 in which said bridge part is of molded insulating material and has, at its under side, a cross rib integrally formed therewith, with a hole molded from the top side

of said bridge part with a portion of the hole overlying and extending into the rib and another portion at that side of the rib that faces generally toward said passageway, thereby to provide a recess for receiving the end of said first-mentioned spring arm.

14. A push switch construction as claimed in claim 9 in which said bridge part and said top wall and spaced side walls are of insulating material and are molded in one piece, said bridge part having, at its underside, a cross-rib integrally formed therewith and extending transversely of the projected area of said opening, said bridge part having a hole molded from the top-side thereof and within the said projected area of said opening, with a portion of the hole overlying and extending into the rib and another portion at that side of the rib that faces generally toward said passageway, thereby to provide a recess for receiving the end of said first-mentioned spring arm.

15. A push switch construction comprising a housing having a top wall provided with an opening and with a plate-like bridge part of insulating material positioned below said top wall, said bridge part having adjacent one end a conductor-connector-contact means with the contact part thereof exposed at the top side of the bridge part, there being a space between said top wall and the other end of said bridge part, a manual push operator of insulating material projecting through said top wall opening, a U-shaped flat spring one arm of which is entered through said space and overlies the top side of the bridge part and also said contact part and engages the under side of said push operator and the other arm of which extends to the under side of the bridge part with the U-shaped bend in the spring extending around the other end of the bridge part, said bridge part having, on its under side and intermediate its ends, transversely extending integrally formed barrier rib means with said conductor-connector means to one side of said barrier means and said second-mentioned spring arm to the other side thereof, and a conductor-binding screw extending through a hole in said last-mentioned spring arm and threaded into said bridge part.

16. A push switch construction as claimed in claim 15,

in which said barrier means and the end of said last-mentioned spring arm have coacting engaging portions that block rotary displacement of said U-shaped spring about the axis of said binding screw.

17. A push switch construction as claimed in claim 15 in which said barrier means is recessed substantially along the plane of the under side of the bridge part for receiving the end of said last-mentioned spring arm upon movement of assembly of said U-shaped spring in a direction to take over said other end of said bridge part and to bring the hole in said spring arm into registry with the threaded hole in the bridge part that receives said binding screw.

18. A push switch construction comprising a housing having a top wall with an opening therein and having an insulating support substantially underlying and spaced downwardly from said top wall, a manual push operator of insulating material in the space above said insulating support and projecting upwardly from said top wall opening, said housing and said push operator having coacting means which guide said push operator for movement in directions inwardly and outwardly of said top wall opening, and circuit-making-and-breaking means coacting between said insulating support and said push operator and comprising a flat conductive element having an end portion resting flatwise against a face of said insulating support, said insulating support having a portion projecting from said face thereof with a hole extending from the opposite face thereof and into said projecting portion to form a recess aligned with said first mentioned face and having said flat end portion of said conductive element enter therein.
